UNITED STATES PATENT OFFICE.

ANDERS ANDERSSON ROSENGREN, OF MALMO, SWEDEN.

AUTOMATIC COUPLING AND CENTRAL BUFFER DEVICE FOR RAILWAY-CARS.

No. 921,564.

Specification of Letters Patent.

Patented May 11, 1909.

Application filed June 8, 1906. Serial No. 320,866.

To all whom it may concern:

Be it known that I, ANDERS ANDERSSON ROSENGREN, a subject of the King of Sweden, and resident of 86 Södra Förstadsgatan, 5 Malmo, in the Kingdom of Sweden, engineer, have invented certain new and useful Improvements in Automatic Coupling and Central Buffer Devices for Railway-Cars, of which the following is a specification, reference being made to the accompanying drawings.

The chief object of this invention is to bring about an automatic coupling and central buffer device that can be employed both 15 at such railway cars which at each end are provided with two buffers (cars arranged according to the "two buffer system"), in which case the said device chiefly serves to automatically couple two cars which collide 20 with each other, although it can also serve, together with the ordinary buffers, to receive the pressure of collision and—after the removal of one of the chief parts of the device—at such railway cars in which the pressure of collision at each end of the car is received by a single buffer situated in the longitudinal central plane of the car (cars arranged according to the "central buffer system"), in which latter case the present device serves both to automatically couple two cars that collide with each other and to receive the whole pressure of collision, *i. e.*, it serves as a central buffer. In addition, the device can be such that, at cars arranged 30 according to the two buffer system, it can be employed for the coupling of a car, which is provided with the said device, to a car provided only with a so-called screw coupling. And, finally, this device is so constructed 35 that its coupling contrivance can be acted upon from either of the sides of the car, so that, from either side, it is possible to uncouple two cars which are coupled together, or to bring about such a position of the said 40 contrivance that two cars that come into collision with each other do not become coupled together.

The device in question consists of three chief parts which, when the device is used at 45 a car arranged according to the two buffer system, lie after each other in the longitudinal central plane of the car and are joined to each other in such a way that they can be disconnected from each other. Of these chief parts the one is suitably arranged for the

automatic coupling of two cars that collide with each other, and, if desired, for receiving a part of the pressure of collision. When the device is being used for the last-named purpose, and when it is at the same time to serve to automatically couple cars, then this part (which in the following specification is called the "coupling piece" or "buffer piece") is rigidly joined to the next chief part (which in the following specification is called the 60 "intermediate piece") which latter part or piece, when the device is such that a car which is provided with it can be coupled to a car which is provided with a screw coupling only, forms the fastening for a screw coupling and a hook belonging to the same. In this use of the device (*i. e.*, at cars arranged according to the two buffer system,) the intermediate piece in its turn is pivotally attached to the third chief part of the device, 65 which third part is connected to the car in such a way that the part can be moved in both directions of the longitudinal direction of the car, while exerting an elastic pressure on the car.

The connection between the intermediate piece and the chief piece last referred to (which in the following specification is called the "draw piece") is such, that the intermediate piece, as well as the coupling piece, 70 as this latter piece is rigidly connected to the intermediate piece, can swing in a horizontal plane. When the device is to serve both to automatically couple together cars and as a central buffer (*i. e.*, is to be used at cars arranged according to the central buffer system), the intermediate piece is removed from the device and the coupling piece is connected direct to the drawpiece in such a way 75 that the former piece can swing in a horizontal plane.

The rigid connection between the coupling piece and the intermediate piece can be eliminated, so that the first-named piece can be swung sidewise and downward, whereby 80 the screw coupling and the hook, which are placed on the intermediate piece, are brought into position to coöperate with corresponding parts of another car.

In the accompanying drawings there is 85 shown as an example an automatic coupling and central buffer device which is constructed in accordance with this invention and is intended for all the three ways of employment described above.

In Figs. 1 and 2 the device is shown as seen from the one side and in plan respectively, and adapted so as to serve, at a car arranged according to the two buffer system, for the 5 automatic coupling of cars and also for receiving a part of the pressure of collision.

In Fig. 3 the device is shown, as seen from the one side, to be adapted to coöperate on a car arranged according to the system just 10 named, with a screw coupling and a hook belonging to the same, on another car.

In Fig. 4 the device is shown, as seen in plan, to be adapted to serve, on a car arranged according to the central buffer system, both to automatically couple the said 15 car to another car, and as a central buffer.

The automatic coupling contrivance of this device can be carried out in any suitable manner. In the present example the contrivance is shown constructed like a so-called 20 American claw, *i. e.*, an arrangement chiefly consisting of a part or hook 1 which can turn around a vertical axis, said part or hook being intended to coöperate with a corresponding 25 part of a similar contrivance for the purpose of holding two cars together, and also of a projection 2, intended to readjust the hook of an approaching claw from its open position to its coupling position. The hook 1 is pivotally mounted in a head 3, from which the projection 2 extends. The claw head 3 is carried by a stem 4; the claw (*i. e.*, the claw head, the hook and the projection), which is also arranged so as to receive 30 the pressure of collision, and the stem form the above-mentioned coupling piece or buffer piece.

The stem 4 is pivotally connected to the intermediate piece 16 by means of a vertical 40 pivot 19. This pivot does not pass through the intermediate piece itself, but through a part 20 which is screwed into the said piece and forms a hook which, when the device is used for the automatic coupling of cars arranged according to the two buffer system, 45 lies in a recess in the inner end of the stem 4. At the just-mentioned use of the device, the coupling piece and the intermediate piece are rigidly attached to each other in some 50 suitable way, *e. g.*, by means of a pin 21, which passes through holes in the stem and through the gap of the hook 20, the cross section of the pin being adjusted to the form of the gap. The pivot 19 also forms the axle 55 of rotation of a screw coupling 23 which, in the use now in question, is hung on the buffer beam by means of a suitable support 24. When the screw coupling is to be used, the pin 21 is drawn up out of the stem 4 and the hook 20; the coupling piece is swung side- 60 wise in the direction indicated by the arrow in Fig. 2 and is, simultaneously or afterward, swung downward (at a rotation of the threaded hook stem in the intermediate piece), so that the parts will come to assume

the position shown in Fig. 3, after which the car can be coupled with a car which is provided with a screw coupling only.

On the sides of the intermediate piece 16 there are lugs 25, attached to springs 26 70 which with their inner ends rest on the outer sides of the beams 27 which, as usual, run in the vicinity of the longitudinal central plane of the car. The springs 26 tend to keep the intermediate piece (and the coupling piece 75 which is rigidly attached to it) in its central position, at the same time that they permit the intermediate piece (and the coupling piece) to perform the requisite lateral movements. The connection between the intermediate piece and the springs 26 must be such, that the intermediate piece can freely move in both directions in the longitudinal direction of the car.

The intermediate piece 16 is by means of 85 a vertical pivot 29 connected to the third chief part of this device, the draw piece 30. This piece is surrounded by a spring 31, which, while exerting an elastic pressure on the car, permits the draw piece and the parts 90 connected with it to move in both directions in the longitudinal direction of the car. The spring 31 is situated between cross pieces 32 and 33 on the draw piece, the one, 32, of which pieces rests against a shoulder on the 95 draw piece (see Figs. 1 and 3), while the other, 33, is retained on the draw piece by means of a pin 34. The cross pieces 32 and 33 act on ridges 35 and 36 which face each other, these ridges being arranged on the 100 inner sides of plates 37 fastened on the inner sides of the beams 27. On the inner sides of the plates 37, between the ridges 35 and 36, there are also other ridges 38, which serve as abutments for the cross pieces 32 105 and 33, if the ridges 35 or 36 should break.

When the device is to be used as a car arranged according to the central buffer system, *i. e.*, both for the automatic coupling of cars and as a central buffer, the intermediate piece 16 is removed and the coupling piece, or the stem 4 respectively, is connected direct to the draw piece 30 by means of the pivot 29 (see Fig. 4). The parts must be so proportioned that the coupling head 3 will 110 come to be situated at the prescribed distance outside the buffer beam. As the stem 4 is now to be acted upon by the springs 26, but as it is unsuitable to have the parts of attachment (the lugs), necessary for the 115 purpose, arranged on the stem, there is inserted into that space in the stem which was previously occupied by the hook 20, a piece 39 which clasps the stem in its transverse direction, and is provided with lugs 40 intended, like the lugs 25 on the intermediate piece 16, to be attached to the springs 26.

As a substitute for the arm 17, which is removed with the intermediate piece 16, the pin 21 can be employed, this pin being ar- 130

ranged in some suitable way so as to serve for this purpose; said pin is pushed down through the holes arranged for it in the stem 4 and through a corresponding hole or recess 5 in the lug piece 39, after which the middle part of the maneuvering shaft 15 is mounted in the same.

It is clear that an automatic coupling and central buffer device constructed in accordance with this invention can, while still retaining the characteristic features of the invention, be carried out in several other ways than the one described. Thus, for example, the draw piece 30 can consist of the draw bar 9 (extending along the whole length of the carriage) at present used in railway cars. It is also clear that such a device can from the beginning be made only for a car arranged according to the two buffer system (with or without a device for coupling on to a screw coupling, in which latter case the coupling piece and the intermediate piece can consist of one piece only), or only for a car arranged

according to the central buffer system (in which case it is superfluous to manufacture 25 the intermediate piece).

Having now described my invention, what I claim as new and desire to secure by Letters Patent is:

In combination with a car, a draw bar 30 comprising a draw piece, an intermediate piece pivotally and detachably connected therewith, a hook having its shank screwing in said intermediate piece, a screw coupling carried by the intermediate piece, a coupling 35 head pivoted to the intermediate piece and having an opening adapted to register with the hook and a pin extending through said opening and through the hook.

In witness whereof I have hereunto set my 40 hand in presence of two witnesses.

ANDERS ANDERSSON ROSENGREN.
